UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Application filed March 28, 1921. Serial No. 456,396

To all whom it may concern:

Be it known that I, ROLANDIS A. BLAIR, a citizen of the United States, residing at Fort Wayne, in the county of Allen and 5 State of Indiana, have invented certain new and useful Improvements in Rail Anchors, of which the following is a specification.

My invention relates to a rail anchor or anticreeper, and a primary object of the invention is to provide a device of this type which will be light, strong, compact, economical to manufacture and so constructed as to have great holding power against the 10 tendency of the rail to creep.

15 A further object is to provide a rail anchor of novel construction which can be used on rails of different sizes and having rail bases of different configuration.

20 A further object is to provide a rail anchor which, in addition to the characteristics referred to above, will take a positive hold on the rail that is not dependent upon the creeping stress of the rail so that, if the device is provided with an abutment, it will 25 hold the rail against longitudinal movement in either direction.

25 A further object is to so construct the rail anchor that it may be removed and replaced repeatedly without impairing its holding power.

30 The invention consists of the new and improved constructions, arrangements, and devices to be hereinafter described and claimed for carrying out the above stated objects and 35 such other incidental objects as will be referred to in the accompanying description.

The invention is illustrated, in certain preferred embodiments, in the accompanying drawings, wherein

40 Fig. 1 is a plan view of one form of rail anchor made in accordance with my invention, the anchor being shown as applied to a rail.

Fig. 2 is a sectional view on line 2—2 of 45 Fig. 1.

Fig. 3 is a fragmentary view, in perspective, of the yoke member of the anchor.

Fig. 4 is a view, similar to Fig. 1, showing a modification.

50 Fig. 5 is a fragmentary view, similar to Fig. 2, showing another modification.

Fig. 6 is a detail view, in side elevation, illustrating the form of key employed in the anchor illustrated in Fig. 5, and

Fig. 7 is a view illustrating a different 55 form of key.

Like characters of reference designate like parts in the several figures of the drawings.

Referring first to Figs. 1, 2, and 3, 10 designates a railway rail and 11 one of the ties 60 supporting the rail. The rail anchor, as shown in these figures, consists of a yoke member 12 and a key 13, the latter being preferably tapered or wedge-shaped. The yoke 12 is made, preferably, of a relatively 65 high carbon steel so as to be resilient. It may be formed by cutting and bending a piece or blank of sheet steel. The yoke member consists of a bar 14 to extend under the base 15 of rail 10, a foot or tie abutting 70 flange 16, and hooks or jaw forming portions 17 and 18 made by bending over the ends of the bar 14. The lip of jaw 18 is longer than that of jaw 17. The jaws are formed with openings 19 and 20 for the key 13 which, as 75 shown in Fig. 2, is driven through openings 19 and 20 between the bottom of rail base 15 and the bar 14 of the yoke member. The key 13 is preferably made of relatively soft steel so as to be tough and unbreakable, 80 but this is not essential. The openings 19 and 20 are preferably arranged in a diagonal line so that the key 13 stands obliquely to the rail. The purpose of this is to check the 85 tendency of the yoke to rock on the key.

The jaws 17 and 18 are preferably formed so that they are bent when the key 13 is driven home. The dotted lines in Fig. 2 indicate, approximately, the original contour of the jaws, the full lines showing the 90 strained contour thereof when the yoke is under the wedging pressure of the key.

In Fig. 4 I have shown a rail anchor like that shown in the preceding three figures except that the openings 19^a, 20^a are disposed 95 so that the key is parallel to the tie.

In Figs. 5 and 6 the yoke 12^b may be formed either like the yoke 12 of Figs. 1 and 2 or the yoke 12^c of Fig. 4. The key 13^b is given a twisting set, the key in this case 100 being of relatively high carbon steel. When the key is driven in between the rail base and the yoke the twist is straightened to a greater or less extent, creating a strain which makes the key self-locking.

105 A similar result may be obtained by giving the key a bend as shown in Fig. 7, the key in this figure being designated 13^c.

It will be seen that the holding power of a rail anchor constructed as above described will be very great in proportion to its size and weight. The device has a resilient engagement with the rail so that its hold thereon is not easily affected by vibration or other disturbing influences. The key has a very gradual taper with consequently little tendency to back out from the position to which it is driven. The lips of jaws 17, 18 are strained when the wedge is driven home. The device is easily applied to a rail by first hooking the jaw 18 over the rail base, raising the yoke and moving it laterally (to the left, Fig. 2) until jaw 17 is engaged with the other edge of the rail base, then driving in the key 13 (or 13^b or 13^c, as the case may be). The device is as easily removed from the rail by driving the key from its small end. The anchor may be used repeatedly without detrimentally affecting its holding power. The same anchor may be used on rails of different sizes and somewhat different cross sectional configurations. For rails beyond the limit of adjustment of any given key the device may be adapted without change in the yoke by merely using a wider or narrower key. The yoke stands at some distance below the bottom of the rail base, particularly at the right hand end (Fig. 2) so that the tie abutting flange 16 does not have to be very long in order to obtain a firm bearing on the tie even when the latter is of the hewn type. Assuming an abutment for the flange 16 on both sides thereof, for example, when imbedded in the ballast the anchor will prevent rail creep in either direction.

I do not claim specifically herein the form of the invention illustrated in Fig. 7 of the drawings. The specific features of this form of the invention are described and claimed in my copending application Serial No. 544,494, filed March 17, 1922.

45 I claim:

1. A rail anchor comprising a rail base embracing yoke provided with resilient jaw portions, and a resilient key adapted to be driven between the under face of the rail base crosswise of the rail and a subjacent portion of the yoke.

2. A rail anchor comprising a rail base embracing yoke provided with resilient jaw portions, and a resilient wedge-shaped key adapted to be driven between the under face of the rail base crosswise of the rail and a subjacent portion of the yoke.

3. A rail anchor comprising a rail base embracing yoke, and a key adapted to be driven between the under face of the rail base crosswise and diagonally of the rail and a subjacent portion of the yoke.

4. A rail anchor comprising a rail base embracing yoke provided with resilient jaw portions and having an opening therein, and

a resilient key adapted to be driven through the opening between the under face of the rail base and a subjacent portion of the yoke.

5. A rail anchor comprising a rail base embracing yoke provided with resilient jaw 70 portions and having an opening therein, and a wedge-shaped resilient key adapted to be driven through the opening between the under face of the rail base and a subjacent portion of the yoke.

6. A rail anchor comprising a rail base embracing yoke formed with resilient jaw portions at opposite ends having openings 80 therein, and a resilient key adapted to be driven through said openings between the under face of the rail base and a subjacent portion of the yoke.

7. A rail anchor comprising a spring metal rail base engaging yoke and a resilient wedge-shaped key adapted to be driven crosswise 85 of the rail between said base and said yoke to effect a rail gripping strain in the latter.

8. A rail anchor comprising a spring metal rail base engaging yoke, and a wedge-shaped key provided with a normal twisted 90 set and adapted to be driven between said base and said yoke to effect a rail gripping strain in the latter.

9. A rail anchor comprising a spring metal rail base engaging yoke, and a key 95 adapted to be driven between said base and said yoke crosswise of the rail to effect a rail gripping strain in the yoke.

10. A rail anchor comprising a spring metal rail base engaging yoke, and a key 100 provided with a normal twisted set and adapted to be driven between the under surface of the rail base and a subjacent portion of the yoke to produce a strain of the yoke.

11. A rail anchor comprising a spring metal rail base engaging yoke formed with an opening and a key adapted to be driven through said opening between the rail base and said yoke to effect a rail gripping strain 105 in the latter.

12. A rail anchor comprising a spring metal rail base engaging yoke formed with openings at opposite ends, and a key adapted to be driven through said openings between the rail base and said yoke to effect a rail gripping strain 115 in the latter.

13. A rail anchor comprising a rail base engaging member having a spring lip to extend over the top of the rail base, and a key adapted to be driven between said rail base and a subjacent portion of said engaging member, to produce a binding strain in 120 said lip.

14. A rail anchor comprising a yoke member having spring lips to engage opposite 125 upper faces of the rail base, and a key adapted to be driven between said rail base and a subjacent portion of said yoke, to produce a binding strain in said lips.

15. A rail anchor comprising a yoke mem- 130

ber having spring lips to engage opposite upper faces of the rail base, and a key adapted to be driven crosswise of the rail between said rail base and a subjacent portion of said yoke, to produce a binding strain in said lips.

16. A rail anchor comprising a yoke member having spring lips to engage opposite upper faces of the rail base, and a wedge-shaped key adapted to be driven between said rail base and a subjacent portion of said yoke, to produce a binding strain in said lips.

17. A rail anchor comprising a yoke member having spring lips to engage opposite upper faces of the rail base and formed at opposite ends with openings, and a key adapted to be driven through said openings between said rail base and a subjacent portion of said yoke.

18. A rail anchor comprising a spring metal yoke member bent at opposite ends to provide lips to overlap opposite edges of the rail base, and a key adapted to be driven between said rail base and a subjacent portion of the yoke, to produce a binding strain in said lips.

19. A rail anchor comprising a spring metal yoke member bent at opposite ends to provide lips to overlap opposite edges of the rail base, and a wedge-shaped key adapted to be driven between said rail base and a subjacent portion of the yoke, to produce a binding strain in said lips.

20. A rail anchor comprising a spring metal yoke member bent at opposite ends to provide lips to overlap opposite edges of the rail base, and a key adapted to be driven crosswise of the rail between said rail base and a subjacent portion of the yoke to produce binding strain in said lips.

21. A rail anchor comprising a spring metal yoke member bent at opposite ends to provide lips to overlap opposite edges of the rail base and formed below the lips with openings, and a wedge-shaped key adapted to be driven through said openings between

the rail base and a subjacent portion of the yoke.

22. A rail anchor comprising a spring metal yoke member formed with a tie abutting foot and bent at opposite ends to provide lips to overlap opposite edges of the rail base and formed below the lips with openings, and a wedge-shaped key adapted to be driven through said openings between the rail base and a subjacent portion of the yoke.

23. A rail anchor comprising a spring metal yoke member bent at opposite ends to provide lips to overlap opposite edges of the rail base, and a key adapted to be driven crosswise and diagonally of the rail between said rail base and a subjacent portion of the yoke to produce binding strain in said lips.

24. A rail anchor comprising a spring metal yoke member bent at opposite ends to provide lips to overlap opposite edges of the rail base, and a key having a twisted set adapted to be driven crosswise of the rail between said rail base and a subjacent portion of the yoke to produce binding strain in said lips.

25. A rail anchor comprising a spring metal yoke member bent at opposite ends to provide lips to overlap opposite edges of the rail base, and a key initially distorted and adapted to be driven through said openings and between the rail base and a subjacent portion of the yoke so as to be straightened thereby.

26. A rail anchor comprising a rail base engaging member provided with a resilient jaw portion and a resilient key, extending crosswise of the rail base, between the under surface thereof and a subjacent portion of said member.

27. A rail anchor comprising a rail base engaging member provided with a resilient jaw portion and a wedge-shaped key, extending crosswise of the rail base, between the under surface thereof and a subjacent portion of said member.

ROLANDIS A. BLAIR.
